(57) **CLAIM**

The ornamental design for an electric fireplace, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of an electric fireplace showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and left side perspective view thereof;

FIG. 8 is a rear, top and right side perspective view thereof;

FIG. 9 is a front, bottom and left side perspective view thereof; and,

FIG. 10 is a front, bottom and right side perspective view thereof.

**1 Claim, 10 Drawing Sheets
(9 of 10 Drawing Sheet(s) Filed in Color)**
